Primary Examiner — Cynthia Ramirez*Assistant Examiner* — Laura H Yu(74) Attorney, Agent, or Firm — JoAnn M. Seaton; Griffiths & Seaton PLLC(57) CLAIM

The ornamental design for a desk organizer, as shown and described.

DESCRIPTION

FIG. 1 is a perspective view of a desk organizer showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines show portions of the desk organizer that form no part of the claimed design. The dash dot lines indicate the bounds of the claimed design and form no part of the claimed design.

1 Claim, 7 Drawing Sheets(56)
